NONSKID DEVICE FOR BATHTUBS AND LIKE FIXTURES

John F. Gutmann, Richmond Hill, N. Y.

Application October 4, 1937, Serial No. 167,151

15 Claims. (Cl. 4—185)

This invention relates to non-skid or anti-slip devices for bath-tubs, shower stalls or cabinets, and the like and has as a main object the provision of such a device for association with the bottom of a bath-tub, in which case the device may be built in the bath-tub, at the factory and made a permanent part thereof, or such device may be constructed as a separate article of manufacture for application to such fixture, in which latter case it would be convenient to build the same in sections fitted into a removable frame which would be suspended or supported from the sides of the fixture.

A further object of the invention is to provide a bath-tub, shower stall or like fixture with anti-slip trays, having a plurality of plungers which are normally kept upward and protruding while floating in water, and capable of being depressed by contact with and weight of parts of the human body. The surrounding protruding plungers will provide a stop wall against slipping.

It is a further object of the present invention to provide an economical and efficient, light in weight and easily cleanable non-slip floor for a bath-tub or similar fixture.

When the device is applied to a tub or similar fixture during its construction, a rim rest is preferably made part of the tub to hold the plunger carrying removable plates, which may be made in sections. The plungers work automatically with the water in the tub when the latter is in use. When applied to tubs which are already in use in homes, these plates are held secure by independent supports which hang over the top edge of the tub. Handles are provided preferably on the plates for removal thereof for cleaning purposes. The plates or the plungers are perforated to provide outlets for the water displaced by the depressed plungers.

Such a device will prevent the occupant from slipping, sliding, skidding or falling, thereby, providing an accident-preventative floor for bath-tubs and like fixtures.

Further objects and advantages of the invention will appear from the following disclosure thereof together with the attached drawings which illustrate certain forms of embodiment thereof. These forms are shown for the purpose of illustrating the invention since the same have been found in practice to give satisfactory and reliable results, although it is to be understood that the various instrumentalities of which the invention consists can be variously arranged and organized and that the invention is not limited to the precise arrangement and organi-

zation of the instrumentalities as herein shown and described.

In the drawings:

Fig. 1 is a perspective view, partly broken away of a form of bath-tub, embodying the invention in one of its aspects.

Fig. 2 is a perspective partial sectional view showing how the device incorporating the invention is applied as part of a bath-tub.

Fig. 3 is a top plan view of a typical frame arrangement and plungers employable in the invention.

Figs. 4—7, inclusive, show some of the many types of plunger heads which may be used in the invention.

Fig. 8 is diagrammatic sectional views of parts of plunger trays, showing various types of plungers which may be used, and how same may be depressed by the weight of a foot.

Fig. 9 is a diagrammatic view of a portion of a tray, showing plunger holes, water holes, handle and grooves.

Fig. 10 is a partial view in section of a shower stall showing the invention applied thereto.

Referring now to the drawings in detail. In Fig. 1, the device is seen as being portable, while in Fig. 2, the device is seen as being built into a bath-tub thus forming an integral part thereof.

The portable device is provided with S shaped straps 26 which engage the rim of the bath-tub 25. These straps support the frame 27. Frame 27 may have a flange or flanges upon which to removably seat the plates or trays 28 of which there may be arranged on frame 27 any desirable number. In Fig. 2 the frame 27 is seen as being supported by the ledge 32 built into or forming part of the side walls of the bath-tub 25 and thereby made integral therewith. The trays or plates 28 may assume any desirable shape. Fig. 3 show some rectangular ones 29 and one with a partly arcuate side wall 30 to conform to the curvature of a bath-tub having a curved rear wall. Of course, in the modern type of bath-tub which has substantially straight walls, the rectangular type of trays or plates 29, above, will suffice.

The frame 27 or 27' is spaced from the bottom of the tub, preferably about six inches to allow for vertical movement of the plungers P. These plungers are arranged to function through suitable openings in the trays or plates 28, 29 and preferably in tubes 31 (Figs. 1 and 8). The plungers P may be of any suitable construction and shape. The tubes or sleeves 31 in which the plungers are arranged for vertical, reciprocal,

slidable movement are secured to the trays and are made in sufficient length as to prevent too free lateral movement of the plungers.

The plungers P may generally comprise a head

- 5 H, a stem or shank S and a float F. The head H may assume any desirable shape, such as for example, triangular (Fig. 4); polygonal (Fig. 5); rectangular (Fig. 6); circular (Fig. 7). The shank may be circular, polygonal or any other 10 desirable shape in cross-section.

It is not only desirable but essential when employing heads H which are other than circular to provide a non-rotatable shank for the plunger to prevent rotation of the latter, otherwise the 15

- plungers by accidental rotation may at times overlap and thereby interfere with each other during their operation. This may be accomplished by providing a shank which is non-circular in cross-section as indicated at 33, or by 20 providing a shank which is keyed as indicated at 34 in a slot 35 within the guide tube 36 (Fig. 8).

The floats F are preferably made of cork C although any other suitable floatable material may be employed; or the floats may be hollow 25 metal members. These floats may be of any desirable shape as shown in Fig. 8. The bottom part of the plunger should be preferably constructed such as to have a tapering, bevelled, slanted or curved portion connecting the shank 30 and float portions to facilitate any accumulation of dirt being washed off during the reciprocating movement of the plunger. Of course, the float may be suitably shaped at its juncture with the shank for the aforesaid purpose.

- 35 The head portion H of the plunger may be made of anti-slip material or the same may be provided with an anti-slip covering 37 (Fig. 8), such as, for example, rubber or fabric.

The trays T may be provided with slidable 40 handles 38 (Fig. 8) to facilitate placement and removal of the same in and from the tub. The grooves 39 (Fig. 8) in the plunger-carrying tray fit into complementary grooves 40 (Fig. 1) of frame 27, thereby providing a smooth and continuous surface between frame and tray.

- 45 To permit the water from surging up from below the trays T when the plungers P are being depressed under the weight of the foot 41 (Fig. 8), holes 42 may be provided in the trays 50 between the plungers, or the plungers may be made hollow as indicated at 43 to provide through passageways for the water.

Fig. 8 shows various sections of trays carrying plungers of different types. These sections 55 have been combined in one figure for purposes of illustration only, it being understood that in carrying out the invention in practice all the plungers should be of the same type. The numeral 44 shows a casing or housing over the cork 60 filler C.

- The foot 41 by the pressure of the body causes the plungers or floats in contact therewith to be depressed allowing the surrounding plungers to act as a wall to prevent slipping or skipping 65 of the foot. The water displaced by the depressed plungers will find an exit through the holes 42 or passages 43.

The chambers 43 or 42' (Figs. 1 and 2) formed by the bottom of the tub and the plates or trays 70 28 fills with water when the water is run into the tub and the floats operate in this chamber to raise the plungers.

75 It is understood that my invention is applicable not only to bath-tubs but also for shower stalls and other fixtures and devices holding or

receiving water and having parts likely to be tread upon by a person.

Where the device is applied to a shower stall, for example, in which there is no provision made to close the drain pipe, it is essential to 5 provide an extension drain sleeve D (Fig. 10) between the trays 29' and the bottom of the stall 25''. The connection between extension D' and the drain D may be effected by employing a rubber hood D''. The extension D' has an opening 10 in the plunger-carrying tray 29', the latter being supported by the flanges or ledges 27' extending from the walls of the stall shower 25''. The floatable plungers operate in the chamber 43'' when filled with water during operation of the 15 shower.

Although the drawings, and the above specification discloses the best modes in which I have contemplated embodying my invention, I desire in no way to be limited to the details of such 20 disclosure, for in the further practical application of my invention many changes in the forms and proportions may be made as circumstances require or experience suggests without departing from the spirit of the invention within the 25 scope of the appended claims.

Having thus described my invention what I claim as new and desire to secure by Letters Patent is:

1. An article of the character described comprising a perforated plate fitting into a receptacle adapted to contain water, and vertically slidable floats operable in said plate and compressible when in surface contact with a part of the human body. 30

2. An article of the character described comprising a perforated plate fitting into a receptacle adapted to contain water, and spaced from the bottom thereof, hollow guides extending within the perforations, and vertically slidable floats operable in said guides and extending therebelow and compressible when in surface contact with a part of the human body. 35

3. An article of the character described comprising a frame fitting into a hollow fixture 45 adapted to contain water, a perforated plate supportable by said frame, and vertically slidable floats operable in said plate and compressible when in surface contact with a part of the human body. 50

4. An article of the character described comprising a perforated plate fitting into a hollow member adapted to contain water, a plurality of floatable plungers vertically operable in the perforations of said plate and extending therebelow, said plungers having smooth, flat upper surfaces for engagement with a part of the human body and compressible when in surface contact therewith. 55

5. An article of the character described comprising a perforated tray fitting into a hollow member adapted to contain water, and spaceable from the bottom thereof, guides extending within the perforations, floatable plungers vertically operable in the guides and extending therebelow, said plungers having smooth and flat upper surfaces for engagement with a part of the human body and compressible when in surface contact therewith. 65

6. An article of the character described comprising a frame fitting into a hollow fixture adapted to contain water and spaceable from the bottom thereof, a perforated tray supportable by said frame, guides extending within the perforations, floatable plungers vertically operable in 70 75

the guides and extending therebelow, said plungers having smooth and flat upper surfaces for engagement with a part of the human body and compressible when in surface contact therewith.

5 7. An article of the character described comprising a perforated plate fitting into a hollow member adapted to contain water, a plurality of floatable plungers vertically operable in the perforations of said plate and extending therebelow, said plungers having smooth, flat upper surfaces for engagement with a part of the human body and compressible when in surface contact therewith, and means for removing said plate.

10 8. An article of the character described comprising a frame fitting into a hollow fixture adapted to contain water and spaceable from the bottom thereof, a perforated tray supportable by said frame, floatable plungers vertically operable in the perforations of said tray and extending therebelow and compressible when in surface contact with a part of the human body, and means to withdraw said tray from said frame.

15 9. An article of the character described comprising a frame fitting into a hollow fixture adapted to contain water and spaceable from the bottom thereof, a perforated tray supportable by said frame, floatable plungers vertically operable in the perforations of said tray and extending therebelow and compressible when in surface contact with a part of the human body, and vertically 20 slideable handles on said tray to withdraw the same from said frame.

25 10. An article of the character described comprising a perforated plate fitting into a hollow member adapted to contain water, a plurality of floatable plungers vertically operable in the perforations of said plate and extending therebelow, said plungers having smooth, flat upper surfaces provided with anti-slip means for engagement 30 with a part of the human body, said plungers compressible when in surface contact therewith.

11. An article of the character described comprising a hollow member adapted to contain water, a frame within said member and spaced from the bottom thereof, a perforated plate supportable by said frame, and floatable plungers vertically slidable in the perforations of said plate and compressible when in surface contact with a part of the human body. 5

12. An article of the character described comprising a hollow member adapted to contain water and provided with a ledge spaced from the bottom thereof, a frame supportable by said ledge, a perforated plate supportable by said frame, and floatable plungers vertically slidable in the perforations of said plate and compressible when in 10 surface contact with a part of the human body. 15

13. An article of the character described comprising a chamber adapted to be filled with water, a top perforated plate for said chamber, and floatable plungers within the perforations of said plate and extending therebelow, said plungers being vertically operable in the chamber by water 20 therein. 20

14. An article of the character described comprising a chamber adapted to be filled with water, a top perforated plate for said chamber, floatable plungers within the perforations of said plate and extending therebelow, said plungers being vertically operable in the chamber by water 25 therein, and outlet means for the water displaced by the plungers. 30

15. An article of the character described comprising a perforated plate fitting into a receptacle adapted to contain water, vertically slideable floats operable in said plate and compressible when in 35 surface contact with a part of the human body, and outlet means for the water displaced by the depressing floats.

JOHN F. GUTMANN. 40
